REWINDER

Sterling W. Warner and Lynn B. Case, New Brunswick, N. J., assignors to John Waldron Corporation, New Brunswick, N. J., a corporation of New Jersey

Application May 8, 1937, Serial No. 141,451

31 Claims. (Cl. 242—66)

This invention relates to strip material rewinders and more especially to such type rewinders in which the rewind roll rests upon a pair of driven rollers which effect rotation of the rewind roll by frictional contact therewith.

An object of this invention is a rewinder of the aforesaid type provided with hydraulic means for supporting independently of the rollers substantially all but a predetermined amount of the total weight of the roll of strip material and associated mechanism so that the weight supported by the rollers will remain substantially constant irrespective of increase in the total weight of the rewind roll as it increases in size.

Other objects, novel features and advantages of this invention will become apparent from the following specification and accompanying drawings, wherein:

20 Fig. 1 is an elevation of one side of a rewinder embodying the invention;

Fig. 2 is an elevation of the other side of said rewinder;

Fig. 3 is a horizontal section substantially on 25 the line 3—3 of Fig. 2 with the rewind spindle empty;

Fig. 4 is a front elevation partly in section;

Fig. 5 is a section on the line 5—5 of Fig. 4;

Fig. 6 is an enlarged section on the line 6—6 30 of Fig. 3, and

Fig. 7 is a diagrammatic view of the oil circuit.

A frame 10 supports a pair of horizontal rollers 11 and 12 which have their shafts journalled in bearings provided on the frame. At one end, the rollers are provided with gears 13 and 14, both of which mesh with a pinion 15 on a shaft 16 suitably journalled in the frame 10. Fixed to the shaft 16 is a pinion 17 which meshes with a pinion 18 mounted on a shaft 19 suitably journalled on the frame 10 and constituting the main drive shaft of the machine. The shaft 19 is driven by any suitable source of power (not shown). Two hollow vertical columns 20 have 45 their lower ends set into the frame 10 and are arranged at either side of the machine. On each column 20 is slidably mounted a head 21 and the shaft of the rewind spindle 22 has its ends journalled in bearings formed on said heads. Each 50 of the bearings comprises an element 23 pivoted to the head and provided with a latch 24 which normally holds it in the position shown in Figs. 1 and 2. The elements 23 are swung away from the position shown in Figs. 1 and 2 to permit easy removal of the rewind spindle from the

heads 21. Each column 20 is provided with a pair of diametrically opposed vertical slots 25 through which each head 21 is connected to an elevating member later to be described.

Into the lower end of each column 20 extends a hollow post 26 having its lower end resting on and fixed to the base of the frame 10. On each post 26 is slidably mounted a sleeve 27 at the lower end of which is provided a stuffing box 27a which forms a liquid-tight seal between the post and sleeve. Each sleeve 27 is provided with a head 27b from which guide members 28 extend through the slots 25 in the column 20 and a mast 29 extends upwardly from the head. The head 21 is attached to the guides 28 for unitary movement with the sleeve 27. A tube 30 surrounds the mast 29 and in the tube is fixed a plug 30a which is engaged by the top of the mast 29. The tube 30 extends through the cap 31 closing the upper end of the column 20. A cap 32 closes the upper end of each tube 30 and includes a frame in which are journalled a pair of sprockets 33. On each column 20 is slidably mounted a carriage 34 and a smoothing or pressing roller 35 has the ends of its shaft journalled in bearings provided on the carriages 34. A bevel gear 36 is provided at one end of the shaft for the roller 35 and meshes with a bevel gear 37 journalled in a bearing formed on one carriage 34. The bevel gear 37 is slidably keyed to a vertical shaft 38 journalled at its upper end in a bearing 39 supported by one cap 31 and at its lower end in a bearing 40 supported by the frame 10. A bevel gear 41 fixed to the shaft 38 meshes with a bevel gear 35 42 fixed to the shaft 16 and through the train of gears just described rotation of the rollers 35 is effected. A shaft 43 has its ends journalled in bearings formed on the carriages 34 and at each end of the shaft is provided a pinion 44 40 which meshes with a rack 45 formed on the column 20.

A shaft 46 has its ends journalled in bearings provided in the caps 31 and at each end of the shaft is provided a pinion 47 which meshes with a rack 48 fixed to the tube 30. A sprocket 49 is fixed to an extension of the shaft 46. A sprocket chain 50 leads upwardly from each carriage 34 over the sprockets 33 and downwardly through a coil spring 51 and is attached to a rod 52, the lower end of which is screw threaded and extends into the screw-threaded bore of a worm wheel 53 journalled in bearings formed on the frame 10. The lower end of the spring 51 is attached to the rod 52 and its upper end 55

is attached to the chain 50 with sufficient slack in the chain to permit full expansion of the spring. Each worm wheel 53 meshes with a worm gear 54 fixed to a shaft 55 extending 5 transversely of the machine and provided at one side of the machine with a hand wheel 56.

A pipe 57 leads to the bottom of each post 26 and through the pipe 57 oil or other suitable liquid is supplied under pressure to the interior of 10 post 26 and sleeve 27 for the purpose of elevating the mast 29 and tube 30 assembly with corresponding elevation of the heads 21. Upon upward movement of the tubes 30, the carriages 34 will be elevated through the medium of the 15 sprocket chains 50 and springs 51 which will expand when subjected to the pull applied by the roller 35 if otherwise unsupported. The carriages 34 are maintained in horizontal alignment by the rack and pinion connections between them 20 and the columns 20. As the tubes 30 are elevated, they cause rotation of the shaft 46 for a purpose later to be described.

A pump 58 has its outlet communicating through suitable piping with the pipes 57 for supplying oil thereto and means are provided for automatically controlling the pressure of the oil supplied to the post 26 as well as for permitting manual regulation. A pipe 58a leads from the outlet of the pump to a valve 59 which will later 30 be described more in detail and a pipe 57a leads from the valve 59 to the pipe 57. Also, a pipe 59b also leads from the valve 59 and communicates with the bottom of the cylinder of a valve C through an inlet portion I. A pipe 59a leads 35 from the outlet port O of the valve C to the inlet of the pump 58. The pipes 58a and 57a conduct oil through the valve 59 to the pipe 57 while the pipe 59a, valve C and a pipe 59b constitute a bypass between the inlet and outlet of the pump 58. 40 A piston 60 projects into said cylinder and is movable to control the effective area of the outlet port O. A lever arm 61 fixed to a shaft 62 suitably journalled in the frame 10 rests upon the head of the piston 60 and a weight W is slidably 45 mounted on the lever arm 61. The pressure of the oil supplied to the cylinders 26 depends upon the position of the weight W and a rod 63 is provided for sliding the weight back and forth on the lever arm. An arm 64 is fixed to the shaft 62 and carries a collar 65 through which extends a rod 66. A coil spring 67 surrounds the rod 66 and is interposed between the collar 65 and a collar 68 attached to the rod 66. The lower end of the rod 66 is attached to a crank arm 69 of a 50 shaft 70 suitably journalled in the frame 10. A sprocket 71 is fixed to the shaft 70 and a sprocket chain 72 passes around the sprockets 49 and 71. The spring 67 opposes the weight W and with the crank arm 69 in the position shown in Fig. 6, 55 exerts its maximum lifting effect on the weight W. Upon elevation of the tubes 30 rotation is effected of the sprocket 49 through the medium of the shaft 48, pinions 47 and racks 48, thereby effecting rotation of the shaft 70 through the 60 intermediary of the sprockets 49 and 71 and sprocket chain 72. The shaft 70 is rotated in such direction that the rod 66 moves downwardly, thereby decreasing the lifting effect of the spring 67 on the lever arm 64, thereby increasing the effect of the weight W on the piston 60. As a result, a higher pressure is required to lift the weight W to open the outlet port O in the valve C with a consequent increased pressure applied by the liquid in the posts 26.

75 The strip material to be rewound is passed from

a feed roll (not shown) under a roller 73 journalled in bearings 74 slidably mounted on vertical posts supported by the frame 10. Springs 75 are interposed between the bearings and nuts 76 so that the roller 73 is resiliently supported. From 5 the roller 73 the strip passes over a second guide roller 73a, then under a series of three guide rollers 73b, 73c and 73d. After leaving the guide roller 73d, the strip passes over the driving and supporting rollers 11 and 12 and around the spindle 22 to which it is attached in any suitable manner. The rewind roll of strip material on the spindle 22 rests on the rollers 11 and 12 and rotation of them effects rotation of the roll by frictional contact. The roller 35 engages the 15 roll of strip material and is driven at slightly slower peripheral speed than the rollers 11 and 12 through the medium of the gearing previously described to smooth and tighten the rolled strip.

At the beginning of the rewind operation, the 20 weight W is set on the arm 61 at such position that oil is supplied to the post 26 and sleeves 27 at the proper pressure nearly to counterbalance the weight carried by the sleeves. As the strip material is wound up on the spindle 22, the 25 weight and diameter of the rewound roll increase. The heads 21 and spindle 22 are moved upwardly by the increase in diameter of the rewind roll with corresponding elevation of the tubes 30 and double upward movement of the roller 35. Upward 30 movement of the tubes 30 effects rotation of the spindle 49 and crank arm 69 as previously described, thereby increasing the effectiveness of the weight W as also previously described, so that the pressure of the oil supplied to the posts 35 26 is increased and the heads 21 support the increased weight of the roll of strip material. The movement of the crank arm 69 is such that the increase of pressure in the oil substantially counterbalances the increase of weight in the 40 rewind roll. Adjustment of the roller 35 relatively to the spindle 22 is effected by vertical movement of the rods 52 through rotation of the worm wheels 53 by the hand wheel 56.

In each cap 31 is provided a dog 31a to engage 45 a notch 31b in the tube 30 to lock the same in elevated position. The two dogs are interconnected by a shaft 31c at one end of which is provided a lever arm 31d to the ends of which are attached rods or wires 31e and 31f by means of 50 which the dogs may be moved into and out of operative position.

The springs 51 provide means for compensating the pressure applied by the roller 35 to the roll of material wound on the spindle 22. The 55 force applied by the roller 35 to the roll of strip material on the spindle 22 may be varied by operation of the hand wheel 56. Rotation of this wheel in such direction as to move the rods 52 downwardly causes expansion of the springs 51 60 with consequent decrease in the force applied by the rolls 35 to the roll of strip material. By means of the adjustment just described, the weight applied to the rewind roller may be regulated in accordance with its width so that the 65 same pressure may be applied to the rewind roll by the roller 35 irrespective of the width of the strip material which is being rewound.

The valve 59 is provided with additional connections which permit manual control of the 70 raising and lowering of the sleeves 27 and their co-operating parts. The valve comprises a tubular casing in which is slidably arranged a piston 86 provided with an operating handle 87. Ports 77, 78, 79, 80 and 81 are provided in the 75

casing and the lower end of the piston 86 has a portion 82 of reduced diameter. The pipe 58a leads to the port 79 while the pipes 57a and 59b lead from the port 78. A pipe 83 leads from the port 77 to the pipe 59a and a pipe 84 leads from the port 80 to the pipe 57. The piston 86 has four operating positions and in Fig. 6 is shown in the first or bottom position. In this position, oil flows from the pump 58 through the pipe 58a, ports 79 and 80 and through pipes 84 and 57 to the port 26. The piston is arranged in its first position when it is desired to elevate the sleeves 27 under manual control. In the second or next higher position of the piston 86, communication is interrupted between the ports 78 and 80 so that oil cannot flow in either direction, thus locking the sleeves 27 in any desired position of elevation. In the third or next higher position of the piston 86, the port 81 is put in communication with the port 78, thus conditioning the device for automatic operation as previously described. In the fourth or highest position of the piston 86, the port 77 is brought into communication with the port 78, thus permitting oil to flow from the post 26 through the pipe 57a and pipe 83 and pipe 59a to the pump inlet, thus permitting descent of the sleeves 27 under manual control. A by-pass 85 between the pump inlet and pump outlet controlled by a suitable relief valve 85a is provided in the usual manner. The valve 59 provides means for disconnecting the automatic valve C and utilizing the total pump pressure to lift the heads 21 to any desired height for the purpose of removing the roll of rewound strip material or for moving the heads and carriages up and down for any other purpose. By reason of the fact that the tubes 30 are slideable on the masts 29, the tubes may be held in elevated position with the masts 29 and sleeves 27 in lowered position. A vent 86 is provided in each tube 30 just below the plug 30a to permit ingress and egress of air upon relative movement of the mast and tube.

We claim:

1. A device of the character described comprising a pair of parallel horizontal rollers, a rewind spindle above said horizontal rollers, means supporting said rewind spindle for vertical movement, a smoothing roller for engagement with strip material wound on said rewind spindle, means supporting said smoothing roller for vertical movement, interconnections between said two vertically movable supporting means for effecting relative movement of said two means with the extent of movement of the second means being substantially twice that of the first means, means for applying hydraulic lifting pressure to said first supporting means, and means for varying said applied pressure.
2. A device of the character described comprising a pair of parallel horizontal rollers, a rewind spindle above said horizontal rollers, means supporting said rewind spindle for vertical movement, a smoothing roller for engagement with strip material wound on said rewind spindle, means supporting said smoothing roller for vertical movement, interconnections between said two vertically movable supporting means for effecting relative movement of said two means with the extent of movement of the second means being twice that of the first means, means for applying hydraulic lifting pressure to said first supporting means, and means for varying said applied pressure in accordance with the elevation of said first means.

3. A device of the character described comprising a frame, a pair of parallel horizontal rollers journaled in said frame, a vertical extensible tubular member at each end of said rollers, each tubular member comprising a fixed and a movable section, means for supplying liquid under pressure to said tubular members, a rewind spindle above said pair of rollers, supporting means for said rewind spindle carried by said movable sections, a smoothing roller above said rewind spindle and adapted to contact with a roll of material in said spindle, means supporting said smoothing roller for vertical movement, a pulley carried by each movable section, a cable passing over each pulley and connected at one end to said last-named means and at its other end to the frame, and means for varying the pressure of the liquid supplied to said extensible tubular members.

4. A device of the character described comprising a frame, a pair of parallel horizontal rollers journaled in said frame, a vertical extensible tubular member at each end of said rollers, each tubular member comprising a fixed and a movable section, means for supplying liquid under pressure to said tubular members, a rewind spindle above said pair of rollers, supporting means for said rewind spindle carried by said movable sections, a smoothing roller above said rewind spindle, means supporting said smoothing roller for vertical movement, pulleys carried by said movable sections, cables passing over said pulleys and connected at one end to said last-named means and at the other end to said frame, and means for varying the pressure of the liquid supplied to said tubular members in accordance with the elevation of said rewind spindle.

5. A device of the character described comprising a frame, a pair of parallel horizontal rollers journaled in said frame, a column at each end of said rollers, an extensible tubular member in each column comprising a fixed and a movable section, means for supplying liquid under pressure to said tubular members, a head slidably mounted on each column, connections between said heads and movable sections for effecting unitary movement thereof, a rewind spindle above said pair of rollers and journaled in said heads, a carriage slidably mounted on each column above said head, a smoothing roller journaled in said carriages, sprockets supported by said movable sections at the upper ends thereof, sprocket chains passing over said sprockets, each chain being connected at one end to one of said carriages and at the other end to said frame, and means for varying the pressure of the liquid supplied to said extensible tubular members.

6. A device of the character described comprising a frame, a pair of parallel horizontal rollers journaled in said frame, a column at each end of said rollers, an extensible tubular member in each column comprising a fixed and a movable section, means for supplying liquid under pressure to said tubular members, a head slidably mounted on each column, connections between said heads and movable sections for effecting unitary movement thereof, a rewind spindle above said pair of rollers and journaled in said heads, a carriage slidably mounted on each column above said head, a smoothing roller journaled in said carriages, sprockets supported by said movable sections at the upper ends thereof, sprocket chains passing over said sprockets, each chain being connected at one end to

end to one of said carriages and at the other end to said frame, and means for varying the pressure of the liquid supplied to said tubular members in accordance with the elevation of said rewind spindle.

7. A device of the character described comprising a frame, a pair of parallel horizontal rollers journalled in said frame, a column at each end of said rollers, an extensible tubular member in each column comprising a fixed and a movable section, means for supplying liquid under pressure to said tubular members, a head slidably mounted on each column, connections between said heads and movable sections for effecting unitary movement thereof, a rewind spindle above said pair of rollers and journalled in said heads, a carriage slidably mounted on each column above said head, a smoothing roller journalled in said carriages, sprockets supported by said movable sections at the upper ends thereof, sprocket chains passing over said sprockets, each chain being connected at one end to one of said carriages and at the other end to said frame, racks on said columns, a shaft journalled in said carriages, pinions fixed to said shaft and meshing with said racks, and means for varying the pressure of the liquid supplied to said tubular extensible members.

8. A device of the character described comprising a frame, a pair of parallel horizontal rollers journalled in said frame, a column at each end of said rollers, an extensible tubular member in each column comprising a fixed and a movable section, means for supplying liquid under pressure to said tubular members, a head slidably mounted on each column, connections between said heads and movable sections for effecting unitary movement thereof, a rewind spindle above said pair of rollers and journalled in said heads, a carriage slidably mounted on each column above said head, a smoothing roller journalled in said carriages, sprockets supported by said movable sections at the upper ends thereof, sprocket chains passing over said sprockets, each chain being connected at one end to one of said carriages and at the other end to said frame, racks on said columns, a shaft journalled in said carriages, pinions fixed to said shaft and meshing with said racks, and means for varying the pressure of the liquid supplied to said tubular members in accordance with the elevation of said rewind spindle.

9. A device of the character described comprising a frame, a pair of parallel horizontal rollers journalled in said frame, a vertical extensible tubular member at each end of said rollers, each tubular member comprising a fixed and a movable section, means for supplying liquid under pressure to said tubular members, a rewind spindle above said pair of rollers, supporting means for said rewind spindle carried by said movable sections, a smoothing roller above said rewind spindle, means supporting said smoothing roller for vertical movement, sprockets carried by said movable sections, sprocket chains passing over said sprockets, each chain being connected at one end to said smoothing roller supporting means, extensible springs connected at one end to said frame and at the other end to said sprocket chains, and means for varying the pressure of the liquid supplied to said tubular members in accordance with the elevation of said rewind spindle.

10. A device of the character described comprising a frame, a pair of parallel horizontal

rollers journalled in said frame, a column at each end of said rollers, an extensible tubular member in each column comprising a fixed and a movable section, means for supplying liquid under pressure to said tubular members, a head slidably mounted on each column, connections between said heads and movable sections for effecting unitary movement thereof, a rewind spindle above said pair of rollers and journalled in said heads, a carriage slidably mounted on each column above said head, a smoothing roller journalled in said carriages, sprockets supported by said movable sections at the upper ends thereof, sprocket chains passing over said sprockets, each chain being connected at one end to one of said carriages, extensible springs connected at one end to said frame and at the other end to said sprocket chains and means for varying the pressure of the liquid supplied to said tubular members in accordance with the elevation of said rewind spindle.

11. A device of the character described comprising a frame, a pair of parallel horizontal rollers journalled in said frame, a column at each end of said rollers, an extensible tubular member in each column comprising a fixed and a movable section, means for supplying liquid under pressure to said tubular members, a head slidably mounted on each column, connections between said heads and movable sections for effecting unitary movement thereof, a rewind spindle above said pair of rollers and journalled in said heads, a carriage slidably mounted on each column above said head, a smoothing roller journalled in said carriages, sprockets supported by said movable sections at the upper ends thereof, sprocket chains passing over said sprockets, each chain being connected at one end to one of said carriages, extensible springs connected at one end to said frame and at the other end to said sprocket chains, racks on said columns, a shaft journalled in said carriages, pinions fixed to said shaft and meshing with said racks, and means for varying the pressure of the liquid supplied to said tubular members in accordance with the elevation of said rewind spindle.

12. A device of the character described comprising a frame, a pair of parallel horizontal rollers journalled in said frame, a vertical extensible tubular member at each end of said rollers, each tubular member comprising a fixed and a movable section, means for supplying liquid under pressure to said tubular members, a rewind spindle above said pair of rollers, supporting means for said rewind spindle carried by said movable sections, a shaft having a rack and pinion connection with said movable sections, and means controlled by the rotation of said shaft for varying the pressure of the liquid supplied to said extensible tubular members.

13. A device of the character described comprising a frame, a pair of parallel horizontal rollers journalled in said frame, a vertical extensible tubular member at each end of said rollers, each tubular member comprising a fixed and a movable section, means for supplying liquid under pressure to said tubular members, a rewind spindle above said pair of rollers, supporting means for said rewind spindle carried by said movable sections, a smoothing roller above said rewind spindle, means supporting said smoothing roller for vertical movement, a pulley carried by each movable section, a cable passing over each pulley and connected at one end to said last-named means and at its other end to

the frame, a shaft having a rack and pinion connection with said movable sections, and means controlled by the rotation of said shaft for varying the pressure of the liquid supplied to said tubular members.

5 14. A device of the character described comprising a frame, a pair of parallel horizontal rollers journalled in said frame, a column at each end of said rollers, an extensible tubular member in each column comprising a fixed and a movable section, means for supplying liquid under pressure to said tubular members, a head slidably mounted in each column, connections between said heads and movable sections for effecting unitary movement thereof, a rewind spindle above said pair of rollers and journalled in said heads, a shaft having a rack and pinion connection with said movable sections, and means controlled by rotation of said shaft for varying 10 the pressure of the liquid supplied to said tubular members.

15 15. A device of the character described comprising a frame, a pair of parallel horizontal rollers journalled in said frame, a column at each end of said rollers, an extensible tubular member in each column comprising a fixed and a movable section, means for supplying liquid under pressure to said tubular members, a head slidably mounted on each column, connections 20 between said heads and movable sections for effecting unitary movement thereof, a rewind spindle above said pair of rollers and journalled in said heads, a carriage slidably mounted on each column above said head, a smoothing roller journalled in said carriages, sprockets supported by said movable sections at the upper ends thereof, sprocket chains passing over said sprockets, each chain being connected at one end to one of said carriages and at the other end to 30 said frame, a shaft having a rack and pinion connection with said movable sections, and means controlled by rotation of said shaft for varying the pressure of the liquid supplied to said tubular members.

40 45. 16. A device of the character described comprising a frame, a pair of parallel horizontal rollers journalled in said frame, a vertical extensible tubular member at each end of said rollers, each tubular member comprising a fixed and a movable section, a rewind spindle above said pair of rollers, supporting means for said rewind spindle carried by said movable sections, a pump for supplying liquid to said tubular members, a by-pass around said pump, a valve in said by-pass, a weighted lever tending to close 50 said valve, and means responsive to the elevation of said rewind spindle for controlling the amount of weight applied to said valve.

45 55. 17. A device of the character described comprising a frame, a pair of parallel horizontal rollers journalled in said frame, a vertical extensible tubular member at each end of said rollers, each tubular member comprising a fixed and a movable section, a rewind spindle above said pair of rollers, supporting means for said rewind spindle carried by said movable sections, a pump for supplying liquid to said tubular members, a by-pass around said pump, a valve in said by-pass, a weighted lever tending to close 60 said valve, a spring opposing the action of said lever, and means responsive to the elevation of said rewind spindle for reducing the effectiveness of said spring.

70 75. 18. A device of the character described comprising a frame, a pair of parallel horizontal

rollers journalled in said frame, a vertical extensible tubular member at each end of said rollers, each tubular member comprising a fixed and a movable section, a rewind spindle above said pair of rollers, supporting means for said rewind spindle carried by said movable sections, a pump for supplying liquid to said tubular members, a by-pass around said pump, a valve in said by-pass, a weighted lever tending to close 10 said valve, a crank arm, a spring interposed between said crank arm and lever, and means actuated by said movable sections for rotating said crank arm to vary the effectiveness of said spring.

15 19. A device of the character described comprising a frame, a pair of parallel horizontal rollers journalled in said frame, a vertical extensible tubular member at each end of said rollers, each tubular member comprising a fixed and a movable section, a rewind spindle above 20 said pair of rollers, supporting means for said rewind spindle carried by said movable sections, a pump for supplying liquid to said tubular members, a by-pass around said pump, a valve in said by-pass, a weighted lever tending to close 25 said valve, a crank arm, a spring interposed between said crank arm and lever, a shaft having rack and pinion connection with said movable sections, and driving connections between 30 said shaft and crank arm.

35 20. A device of the character described comprising a frame, a pair of parallel horizontal rollers journalled in said frame, a column at each end of said rollers, an extensible tubular member in each column comprising a fixed and a movable section, a head slidably mounted on each column, connections between said heads and movable sections for unitary movement thereof, a rewind spindle above said rollers and journalled in said heads, a shaft supported by 40 said columns and having a rack and pinion connection with each movable section, a pump for supplying liquid to said tubular members, a by-pass around said pump, a valve in said by-pass, a weighted lever tending to close 45 said valve, and means operated by said shaft for controlling the amount of weight supplied to said valve.

50 21. A device of the character described comprising a frame, a pair of parallel horizontal rollers journalled in said frame, a column at each end of said rollers, an extensible tubular member in each column comprising a fixed and a movable section, a head slidably mounted on each column, connections between said heads and movable sections for unitary movement thereof, a rewind spindle above said rollers and journalled in said heads, a shaft supported by said columns and having a rack and pinion connection with each movable section, a pump for supplying liquid to said tubular members, a by-pass 55 around said pump, a valve in said by-pass, a weighted lever tending to close said valve, a spring opposing the action of said lever, and means operated by said shaft for reducing the effectiveness of said spring.

60 22. A device of the character described comprising a frame, a pair of parallel horizontal rollers journalled in said frame, a column at each end of said rollers, an extensible tubular member in each column comprising a fixed and a movable section, a head slidably mounted on each column, connections between said heads and movable sections for unitary movement thereof, a rewind spindle above said rollers and journalled in said heads, a shaft supported by 70 75

- 5 said columns and having a rack and pinion connection with each movable section, a pump for supplying liquid to said tubular members, a by-pass around said pump, a valve in said by-pass, a weighted lever tending to close said valve, a crank arm, a spring interposed between said crank arm and lever, and driving connections between said shaft and crank arm for rotating the latter to vary the effectiveness of said spring.
- 10 23. A device of the character described comprising a frame, a pair of parallel horizontal rollers journaled in said frame, a column at each end of said rollers, an extensible tubular member in each column comprising a fixed and a movable section, a head slidably mounted on each column, connections between said heads and movable sections for unitary movement thereof, a rewind spindle above said rollers and journaled in said heads, a shaft supported by said columns and having a rack and pinion connection with each movable section, a carriage 15 slidably mounted on each column above said head, a smoothing roller journaled in said carriages, sprockets supported by said movable sections at the upper ends thereof, sprocket chains passing over said sprockets, each chain being connected at one end to one of said carriages and at the other end to said frame, a pump for supplying liquid to said tubular members, a by-pass 20 around said pump, a valve in said by-pass, a weighted lever tending to close said valve, and means operated by said shaft for controlling the amount of weight supplied to said valve.
24. A device of the character described comprising a frame, a pair of parallel horizontal rollers journaled in said frame, a column at each end of said rollers, an extensible tubular member in each column comprising a fixed and a movable section, a head slidably mounted on each column, connections between said heads and movable sections for unitary movement thereof, a rewind spindle above said rollers and journaled in said heads, a shaft supported by said columns and having a rack and pinion connection with each movable section, a carriage 25 slidably mounted on each column above said head, a smoothing roller journaled in said carriages, sprockets supported by said movable sections at the upper ends thereof, sprocket chains passing over said sprockets, each chain being connected at one end to one of said carriages, extensible springs connected at one end to said frame and at the other end to said sprocket 30 chains, a pump for supplying liquid to said tubular members, a by-pass around said pump, a valve in said by-pass, a weighted lever tending to close said valve, and means operated by said shaft for controlling the amount of weight supplied to said valve.
- 35 27. A device of the character described comprising a frame, a pair of parallel horizontal rollers journaled in said frame, a column at each end of said rollers, an extensible tubular member in each column comprising a fixed and a movable section, a head slidably mounted on each column, connections between said heads and movable sections for unitary movement thereof, a rewind spindle above said rollers and journaled in said heads, a shaft supported by said columns and having a rack and pinion connection with each movable section, a carriage 40 slidably mounted on each column above said head, a smoothing roller journaled in said carriages, sprockets supported by said movable sections at the upper ends thereof, sprocket chains passing over said sprockets, each chain being connected at one end to one of said carriages, extensible springs connected at one end to said frame and at the other end to said sprocket 45 chains, a pump for supplying liquid to said tubular members, a by-pass around said pump, a valve in said by-pass, a weighted lever tending to close said valve, and means operated by said shaft for controlling the amount of weight supplied to said valve.
- 45 28. A device of the character described comprising a frame, a pair of parallel horizontal rollers journaled in said frame, a column at each end of said rollers, an extensible tubular member in each column comprising a fixed and a movable section, a head slidably mounted on each column, connections between said heads and movable sections for unitary movement thereof, a rewind spindle above said rollers and journaled in said heads, a shaft supported by said columns and having a rack and pinion connection with each movable section, a carriage 50 slidably mounted on each column above said head, a smoothing roller journaled in said carriages, sprockets supported by said movable sections at the upper ends thereof, sprocket chains passing over said sprockets, each chain being connected at one end to one of said carriages, extensible springs connected at one end to said frame and at the other end to said sprocket 55 chains, a pump for supplying liquid to said tubular members, a by-pass around said pump, a valve in said by-pass, a weighted lever tending to close said valve, a spring opposing the action of said lever, and means operated by said shaft for reducing the effectiveness of said spring.
- 55 29. A device of the character described comprising a frame, a pair of parallel horizontal rollers journaled in said frame, a column at each end of said rollers, an extensible tubular member in each column comprising a fixed and a movable section, a head slidably mounted on each column, connections between said heads and movable sections for unitary movement thereof, a rewind spindle above said rollers and journaled in said heads, a shaft supported by said columns and having a rack and pinion connection with each movable section, a carriage 60 slidably mounted on each column above said head, a smoothing roller journaled in said carriages, sprockets supported by said movable sections at the upper ends thereof, sprocket chains passing over said sprockets, each chain being connected at one end to one of said carriages, extensible springs connected at one end to said frame and at the other end to said sprocket chains, a pump for supplying liquid to said tubular members, a by-pass around said pump, a valve in said by-pass, a weighted lever tending to close said valve, a spring opposing the action 65 of said lever, and means operated by said shaft for reducing the effectiveness of said spring.
- 60 30. A device of the character described comprising a frame, a pair of parallel horizontal rollers journaled in said frame, a column at each end of said rollers, an extensible tubular member in each column comprising a fixed and a movable section, a head slidably mounted on each column, connections between said heads and movable sections for unitary movement thereof, a rewind spindle above said rollers and journaled in said heads, a shaft supported by said columns and having a rack and pinion connection with each movable section, a carriage 70 slidably mounted on each column above said head, a smoothing roller journaled in said carriages, sprockets supported by said movable sections at the upper ends thereof, sprocket chains passing over said sprockets, each chain being connected at one end to one of said carriages, extensible springs connected at one end to said frame and at the other end to said sprocket chains, a pump for supplying liquid to said tubular members, a by-pass around said pump, a valve in said by-pass, a weighted lever tending to close said valve, a spring opposing the action 75 of said lever, and means operated by said shaft for reducing the effectiveness of said spring.

head, a smoothing roller journalled in said carriages, sprockets supported by said movable sections at the upper ends thereof, sprocket chains passing over said sprockets, each chain being connected at one end to one of said carriages, 5 extensible springs connected at one end to said frame and at the other end to said sprocket chains, a pump for supplying liquid to said tubular members, a by-pass around said pump, a valve in said by-pass, a weighted lever tending to close said valve, a crank arm, a spring interposed between said crank arm and lever, and driving connections between said shaft and crank arm for rotating the latter to vary the 10 effectiveness of said spring.

15 29. A device of the character described ac-

cording to claim 26 characterized by racks on said columns, a shaft journalled in said carriages and pinions fixed to said shaft and meshing with said racks.

30. A device of the character described according to claim 27 characterized by racks on 5 said columns, a shaft journalled in said carriages and pinions fixed to said shaft and meshing with said racks.

31. A device of the character described according to claim 28 characterized by racks on 10 said columns, a shaft journalled in said carriages and pinions fixed to said shaft and meshing with said racks.
